Patented Jan. 15, 1918.

2 SHEETS—SHEET 1.

A technical line drawing of a wire mesh structure, likely a trap or cage, shown in perspective. The structure consists of a top wire mesh (1) supported by a frame (2). Below the mesh is a stack of several rectangular panels (3). The bottom-most panel is labeled with dimensions: 151 (width), 150 (height), 150 (depth), and 150 (thickness). Above this panel are four smaller panels, each labeled with dimensions: 150 (width), 150 (height), 150 (depth), and 150 (thickness). The top-most panel (3) is labeled with dimensions: 150 (width), 150 (height), 150 (depth), and 150 (thickness). The entire assembly is labeled with the number 11. Handwritten labels are present: 'Fig. 1.' in the top left, 'Fig. 2.' in the bottom left, and 'Fig. 3.' in the bottom right.

Inventor

D. H. Otis,

E. O. Groome & Co.

his Attorney's

UNITED STATES PATENT OFFICE.

DANIEL H. OTIS, OF MADISON, WISCONSIN.

BOOKKEEPING SYSTEM.

1,253,714.

Specification of Letters Patent. Patented Jan. 15, 1918.

Application filed June 12, 1915. Serial No. 33,708.

To all whom it may concern:

Be it known that I, DANIEL H. OTIS, a citizen of the United States of America, residing at Madison, in the county of Dane and State of Wisconsin, have invented certain new and useful Improvements in Improved Bookkeeping Systems, of which the following is a specification, reference being had therein to the accompanying drawing.

10 This invention relates to registers for bookkeeping purposes and is especially designed for facilitating the keeping of farm accounts or household accounts.

One important object of the present invention is the production of a simple account or register book wherein the accounts are not required to be posted and wherein a minimum description is necessary for accurately keeping an account of the several 20 items necessary to be recorded.

Another object of this invention is the production of a simple register or recording book, wherein the disbursements are recorded on opposite pages with respect to 25 the receipts.

A still further object of this invention is the production of a simple loose-leaf guide which is adapted to be used in connection with the register book for permitting the 30 several items necessary to be entered to be placed in their proper columns within the minimum amount of time.

With these and other objects in view, this invention consists of certain novel combinations, constructions, and arrangements of parts, as will be hereinafter fully described and claimed.

In the accompanying drawings:—

Figure 1 is a perspective view of the book 40 employed in the present invention.

Fig. 2 is a plan view thereof, showing simple pages arranged for the purpose of facilitating a clear understanding of the method of entering the several items.

45 Fig. 3 is an enlarged plan view of one of the disbursement sheets, showing the indicator used in connection therewith.

Fig. 4 is an enlarged view of the top portion of one of the receipt sheets.

50 Fig. 5 is a plan view partly broken away, showing the arrangement of the indicating items upon the indicator.

Fig. 6 is a perspective view of a portion of the indicator.

55 Fig. 7 is a plan view of the inner face of

the indicator or in fact of one side of the indicator, showing the manner in which a decimal system may be employed for the purpose of adding additional items which it may be desired to enter upon the register. 60

Referring to the accompanying drawings it will be seen that the present register sheets employed are preferably arranged in book-like formation within a binding 1. A plurality of record receiving sheets 2 are placed 65 between the binding 1 and are arranged in step-like position as indicated by the numeral 3 in Fig. 1, whereby the total disbursements for each month may be conveniently read and the total disbursements 70 conveniently added without the necessity of posting the disbursements after having once been entered upon the recording register sheets 2. It should be understood that these sheets 2 are arranged in this step-like relation so as to permit sufficient space at the bottom of each register or record sheet 2 to permit the total disbursements for each month to be easily read. The arrangement of the bottom portions of the sheets 2 may 75 also be clearly seen by referring to Fig. 2 of the drawings. It should be understood that the disbursements are registered or entered upon the right-hand sheet as indicated in Fig. 2, whereas the receipts are entered 80 upon the left-hand sheet, so that the disbursements and receipts will appear upon opposite pages and may be readily compared for each month.

Both the receipt and disbursement sheets 90 are ruled in vertical columns, lettered from "A" to "Q" inclusive, for the purpose of constituting guides for the indicator slip adapted to be used therewith. Below the indicating letters in the column 4 is arranged 95 a transversely extending column 5 within which is arranged a series of headings indicating the general classification of receipts and disbursements, each general heading being arranged in one of the vertical columns 100 indicated by the letters "A" to "Q" inclusive. Each of the columns indicated by the letters "A" to "Q" inclusive is in turn divided into a plurality of sub-columns 6. The day and month are arranged in calendar 105 relation along the edge of each of the receipt and disbursement sheets in the column indicated by the numeral 7 whereby, with the use of the indicator 8 the disbursements and receipts for each day may be easily and 110

readily entered in the proper space opposite the date upon which the receipts are received or the disbursements made.

As above described, a special indicator in the nature of a detachable or loose-leaf is employed, constituting a detachable folder comprising two hinged leaves and having printed thereon in the top transversely extending column 9 over the vertically extending columns 10 indicated by the letters "A" to "Q" inclusive the following notation: "Ind. No."—"Quan.—value." Each of these indicating titles is divided by a vertically extending line for producing three sub-columns 15 in each of the main columns 10 of the indicator 8. Below the designating letters "A" to "Q" inclusive upon the indicator 8 is arranged a transverse row of titles similar to the titles appearing below the letters "A" to "Q" inclusive upon the receipt and distributing sheets. These designating letters and titles will facilitate the proper registration of the columns upon the indicator 8 with respect to the receipt and disbursement sheets of the register.

In order to save space and time in entering each item in the record, the several items under each general classified head are designated by an indicating number, such for instance as barley is indicated by the numeral 1, corn by the numeral 2, cotton by the numeral 3, etc.; appearing under the general classified head of field crops. The above description has reference to that portion of the indicator which is used in connection with the receipt pages of the register. Upon the opposite sheet of the indicator, the items which would be known as disbursements are also indicated by numerals in a column under the head of indicating numerals such for instance as land, indicated by the numeral 1, house by the numeral 2, etc.; appearing under the general head of permanent improvements, machinery, etc. It will therefore be seen that by applying the proper numeral in the column for indicating numerals and the amount received or disbursed in the adjoining column indicated by the abbreviation "Quan." and placing the value 50 in the column above the word "value" upon the receipt or disbursement sheets, the article, quantity and price will appear correctly, opposite the day upon which the disbursement is made or the receipts received. Furthermore, it should be understood that at the end of each month the totals may be obtained and it is not necessary to post or re-enter any of the total amounts, owing to the stepped relation of the respective pages for 60 disbursements and receipts.

By referring to Fig. 2 it will be seen that the figures or symbols, representing the items to be recorded on the register sheet are placed in the small space or sub-column 85 formed by the vertical line on the left of

each column containing the headings. By considering Fig. 2 it will be seen that in the upper left hand corner of said figure, the numeral 2 in the sub-column on the left of the main column containing the heading "Field crops" indicates the item to be recorded on the register sheet, and the numerals 12 indicate the quantity of the product. In the column headed "Poultry and eggs" 4 separated from 20 by a vertical line reading 4 | 20 indicates the cost of 20 dozen of eggs, which would be \$4.20 and 6 separated from 20 by a vertical line reading 6 | 20 indicates the quantity of eggs, "6" indicating the eggs and "20" the quantity—20 dozen.

Attention is now called to Fig. 7 and for the purpose of illustration the decimal system has been employed arranged in the same general classes as that described upon the front face of the indicator, these additional indicating means preferably being employed upon the inner face of the indicator. For further reference it should be understood that items such as wagons, harness, etc., may be indicated by the decimals .7 and .8. Other suitable decimal indications may be employed without departing from the spirit of the invention and such change may be made according to the desire of the person who has charge of entering the several items upon the disbursement or receipt sheets.

As above described, the indicator is preferably formed of two leaves so as to fit conveniently between the disbursement and receipt pages so that the same may be easily turned with the pages and permit the vertical columns or lines formed thereon to easily register under their proper headings.

It should be understood that the same system described with respect to farming accounts may also be employed for household accounts merely by changing the wording of the indicating titles in the respective columns. It should be noted that by entering the receipts and disbursements on opposite pages, the totals for each month are so arranged that the totals may be added and secured for the entire year without transferring or posting. The varying lengths of the income pages permit not only the recording of the total incomes of each month in such a way as to have the totals for the various months in proper order and in plain view for the yearly totals, but they also serve as an index in referring to the record of any given month. It should be further understood that the loose narrow double leaf guide 8 contains the same headings and sub-headings or descriptions for recording farm, household, and similar transactions. These sub-headings as previously described are given indicating numbers. It should be borne in mind that one of the very important features of the present invention is the formation 130

of the loose-leaf indicator whereby the same may be readily and conveniently transferred from one page to another, and it should be further understood that the loose-leaf indicator performs an important function in quickly locating the line and column in which the transaction is to be recorded. Again, the indicator by being a double page hinged at one edge, makes it possible to record expenses on one side and incomes on the other.

Of course suitable summary sheets are employed in connection with the book for a summary of the entire work when the book has been entirely used, but, as these sheets do not form a part of the invention and may be arranged in any suitable or desired manner for the purpose of convenience, it of course is not necessary to go into a lengthy description of such summary pages, such as the entrance of the amount of real estate and the amount of material which is on hand at the end or beginning of each year.

What I claim is:—

A book for bookkeeping comprising several series of stepped leaves having a plurality of vertically arranged columns ruled

thereon, each page provided with a plurality of transversely extending columns ruled thereon, indicating means printed upon said columns, a calendar arranged along the edge of each sheet for permitting the entrance of items upon the day of expenditure or receipt, of a loose leaf indicator ruled similarly and indicated similarly to said receipt and disbursement pages, said loose leaf indicator provided with a plurality of rows of items, each having a special indicating number whereby said indicating number of said loose leaf indicator may be applied in a proper column upon said disbursement or receipt pages for permitting the convenient recording of items upon said receipt and disbursement sheets, said loose leaf indicator being entirely separate from said disbursement sheets and comprising a pair of leaves and having a table printed upon the inner face of said leaves for constituting a key to identify certain articles to be entered in the different columns upon said sheets.

In testimony whereof I hereunto affix my signature.

DANIEL H. OTIS.
